GUY CARLTON OLIVER, OF WHITTIER, CALIFORNIA, ASSIGNOR OF ONE-HALF TO
ROLAND R. CRUM, OF LOS NEITOS, CALIFORNIA

DRILLING BIT

Application filed June 26, 1929. Serial No. 373,883.

This invention relates to drilling bits.

The general object of this invention is to provide an improved drilling bit.

A more specific object of the invention is to provide an improved drilling bit having cutting members of novel form.

Another object of the invention is to provide a drilling bit including a body having a plurality of drill shares mounted thereon.

10 A further object of the invention is to provide a bit having pairs of opposed cutting members thereon with a pair of said members extending throughout the full diameter of the bit and with another pair of members 15 having their outer edges disposed within the cutting periphery of the others.

Another object of the invention is to provide a drilling bit wherein the drilling members have an angular clearance from the 20 front to the rear of the blade and wherein the rear is lower than the front.

Another object of the invention is to provide a curved drilling bit wherein the leading face of the blade cuts to one diameter 25 and wherein the sweep of the blades cuts to a lesser diameter.

Another object of the invention is to provide a drilling bit including a plurality of independent cutting surfaces so arranged that 30 the opposed cutting surfaces are similar and wherein the interposed cutting surfaces are similar but of a different size from the first surfaces.

Another object of the invention is to provide 35 a drill having a fixed curved cutting blade wherein the curvature of the blade is struck with a radius differing from the radius of the hole which the bit makes.

Another object of the invention is to provide 40 a drilling bit having a plurality of cutting members comprising teeth having trailing wings so arranged that the trailing portion performs the cutting functions where the preceding portion leaves off.

45 Other objects and the advantages of this

invention will be apparent from the following description taken in connection with the accompanying drawings wherein:

Fig. 1 is a side elevation of my improved bit.

Fig. 2 is a bottom plan view of the bit shown in Fig. 1.

Fig. 3 is a cross section of my bit taken on line 3—3 of Fig. 1.

Fig. 4 is a view similar to Fig. 2 showing 55 the manner in which the blades cut.

Fig. 5 is a view similar to Fig. 3 of a modification of my invention wherein the bit includes a core drill, and

Fig. 6 is a bottom plan view of the drill 60 shown in Fig. 5.

Referring to the drawings by reference characters I have indicated my improved bit generally at 10. As shown this bit comprises a body portion 12 having integral wings 13 65 extending therefrom in cruciform shape. Within the body 12 I provide a recess 14 which is partly threaded as at 15 for securing the bit in service position.

On each of the wings 13 I show two cutting blades 16 although the number of blades may be varied as desired. These blades extend transversely of the wing and include cutting faces 17 and trailing cutting faces 18. The front faces 17 have cutting edges 75 17'. Each of the blades 16 is so formed that the trailing edge 19 thereof is closer to the longitudinal axis of the bit than the cutting face 17, thus cutting edge 17' and the face 17 cut one portion of the formation while the 80 trailing cutting face 18 cuts another portion of the formation as clearly shown in Fig. 4.

The cutting edge 17' of the face 17 is so formed that the outer end of the edge is in 85 advance of the inner end of the edge when the device is rotated in an operative direction.

The cutting faces 18, which are in reality bottom faces, of each blade taper upwardly 90

towards the trailing edge while the face 18 also extends inwardly. The blades on the outer face are tapered as at 20 to form a relieved portion.

5. By providing the various tapers on the blades 16 the cutting surfaces thereof are self sharpening which assures a highly efficient operation of the bit.

The blades are shown as curved but may 10 be straight if desired, although I now prefer the curved blade.

As shown the outer blades 16^a on opposed wings 13 are evenly spaced from the axis of the bit and the inner blades 16^b are also 15 evenly spaced from the axis. The blades 16^c and 16^d are also evenly spaced but the latter blades are nearer the axis than are the blades 16^a and 16^b respectively. Thus the blades on opposed wings cut one portion of 20 the formation and the blades on the wings at right angles thereto cut another portion of the formation as clearly shown in Fig. 4.

It will be understood however, that other spacing of the blades 16 may be employed, 25 such as spacing all the blades a different distance from the longitudinal axis of the bit so that they all cut different portions of the formation.

On the bottom of one of the wings 16 I 30 may provide a fish tail bit 22 which is of conventional form and includes cutting surfaces 23 adapted to cut the formation not cut by the inner blades 16 as shown in Fig. 4.

In the body portion 12 I provide a plurality of apertures 24 which are positioned intermediate the wings 13 and form passageways from the recess 14 to the exterior of the body for the passage therethrough of the 35 circulating fluid.

40. In Figs. 5 and 6 I have indicated generally at 25 a slight modification of my bit wherein in place of the fish tail bit 22 I provide a core drill indicated at 26. As shown the core drill 26 includes a plurality of bottom cutting teeth 27 surrounding an aperture 28 which communicates with the recess 14 in the body 12. A portion of the aperture 28 adjacent the recess 14 is threaded as at 20 to receive similar threads on a core barrel 50 30 to removably secure it thereto. Positioned outside of the bottom teeth 27 I provide a plurality of blades 32 which are preferably arranged one on each wing, and include a cutting edge face 33 and a bottom cutting 55 surface 34. The outermost edge of the face 33 of each of the blades 32 is preferably in advance of the rest of the face when the device is rotated in an operative direction and the outermost or advanced edge of the faces 60 33 of the blades 32 is preferably on the same plane as the advance edges of the faces 17 of the blades 16 on the corresponding wing when the plane is taken from the longitudinal center of the bit to the outermost edge 65 65 of the face 17 of the outer blade 16.

The bottom cutting surfaces 33 of the blades 32 are preferably positioned in advance of the lowermost surface of the blades 17 and the bottom cutting teeth 27 are preferably positioned in advance of the bottom cutting surface 33 of the blades 32. By positioning the core teeth and blades in advance of the blades 16 the circulating fluid is prevented from entering the aperture 28 and washing the core out. 70

The blades 32 are shown as extending outwardly different distances from the longitudinal axis of the bit and the blades 16 cut the formation not previously cut by the teeth 27 and the blades 32. 80

From the foregoing description it will be apparent that I have provided a novel drilling bit which is simple in construction and highly efficient in operation.

Having thus described my invention, I 85 claim:

1. In a drill bit, a body, wings on said body, said wings comprising a plurality of pairs, with the wings of each pair arranged on opposite sides of the axis of said body, a plurality of arcuate cutting blades arranged in spaced relation on each wing, said blades having a front cutting edge and a narrower trailing cutting portion, said front cutting portion being disposed farther from the axis 95 of said bit than the said trailing portion.

2. In a drill bit, a body portion, wings on said body, said wings being arranged in cruciform shape, a plurality of cutting blades arranged on each of said wings, and extending transversely thereof, said cutting blades depending from said wings and extending below the bottom of said body portion, the lower face of said cutting blades being arranged in a plane which inclines upwardly 100 towards the axis of said bit and which inclines upwardly towards the trailing end of said blades, said cutting blades on opposed wings being evenly spaced from the longitudinal axis of said bit with one set of blades closer to the longitudinal axis of said bit than the other set of blades. 105

3. In a drill bit, a body portion, wings on said body, said wings extending beyond the outer periphery of said body and being arranged in cruciform shape, a plurality of cutting blades arranged on each of said wings and extending transversely thereof, said cutting blades depending from said wings and extending below the bottom of said body portion, the lower face of said cutting blades being arranged at an obtuse angle relative to the longitudinal center of said bit, each of said cutting blades including a cutting edge with the lower face of said cutting blades being tapered upward from said cutting face towards the rear of said blades, a portion of the outer face of said blades being relieved at the rear of said cutting faces, said cutting blades on opposed wings being evenly spaced 110

115

120

130

- from the longitudinal axis of said bit and being spaced a different distance from the longitudinal axis of said bit from those which are on the wings at right angles thereto.
- 5 4. In a drill bit, a body including a top portion and wings on said body, said wings comprising a plurality of pairs, with the wings of each pair arranged on opposite sides of the axis of said body, a plurality 70
10 of arcuate cutting blades arranged in spaced relation on each wing and extending transversely thereof, said blades having a front cutting edge and a narrower trailing cutting portion, said front cutting portion being disposed farther from the axis of said bit than the said trailing portion, the front edge of each blade being disposed farther from the top of said bit than the trailing portion, the blades of one pair of wings being 75
15 adapted to cut one zone of formation and the blades of another pair being adapted to cut a different zone of formation.
5. In a drill bit, a body portion, wings on said body, said wings extending beyond the 80
20 outer periphery of said body and being arranged in cruciform shape, a plurality of cutting blades arranged on each of said wings and extending transversely thereof, said cutting blades depending from said wings and 85
25 extending below the bottom of said body portion, each of said cutting blades including a cutting edge with the lower face of said cutting blades tapered upward from said cutting edge towards the rear of said blades, a 90
30 portion of the outer face of said blades on the rear thereof being relieved, said cutting blades on opposed wings being equally spaced from the longitudinal axis of said bit and being spaced a different distance from the longitudinal axis of said bit from those on the 95
35 wings which are at right angles thereto and a fish tail bit on the lower end of said body and spaced from said cutting blades.
6. In a drill bit, a body, wings on said 100
40 body, said wings comprising a plurality of pairs, with the wings of each pair arranged on opposite sides of the axis of said body, one pair of wings having a plurality of cutting blades arranged in spaced relation thereon, 105
45 a cutting blade on each of the remaining wings, said first mentioned cutting blades having a front cutting edge and a narrower trailing cutting portion, the front cutting portion of certain blades being disposed farther from the axis of said bit than the trailing cutting portion.
7. In a drill bit, a body portion, wings on 110
50 said body, said wings being arranged in cruciform shape, a plurality of cutting blades arranged on said wings, and extending transversely thereof, said cutting blades including a front cutting portion and a trailing portion, said cutting blades depending from said wings and extending below the bottom of said 115
55 body portion, the lower face of said cutting 120
60 blades being arranged in a plane which inclines upwardly towards the axis of said bit and which inclines upwardly towards the trailing end of said blades, said cutting blades on opposed wings being evenly spaced from the longitudinal axis of said bit with one set of blades closer to the longitudinal axis of said bit than the other set of blades.
- In testimony whereof, I hereunto affix my 75
65 signature. GUY CARLTON OLIVER.
